Primary Examiner — Khawaja Anwar*Assistant Examiner* — Taylor O Mortorff(74) *Attorney, Agent, or Firm* — Browdy and Neimark, PLLC(57) **CLAIM**

The ornamental design for an iron, as shown and described.

DESCRIPTION

FIG. 1 is a perspective view of an iron according to the present design;

FIG. 2 is a front view thereof;

FIG. 3 is a rear view thereof;

FIG. 4 is a left side view thereof;

FIG. 5 is a top plan view thereof;

FIG. 6 is a bottom plan view thereof; and,

FIG. 7 is a perspective view showing the iron of FIG. 1 resting on a charging pad.

The right side of the iron according to the present design is a mirror image of the left side view.

The subject matter shown in broken lines are for illustrative purposes only and form no part of the claimed design.

1 Claim, 5 Drawing Sheets---
